UNITED STATES PATENT OFFICE.

JOHN B. LOGAN AND ABNER GREENLEAF, OF BALTIMORE, MARYLAND.

FIRE-EXTINGUISHING APPARATUS.

SPECIFICATION forming part of Letters Patent No. 226,919, dated April 27, 1880.

Application filed August 18, 1879.

To all whom it may concern:

Be it known that we, JOHN B. LOGAN and ABNER GREENLEAF, of Baltimore, in the county of Baltimore and State of Maryland, have invented certain new and useful Improvements in Apparatus for Extinguishing Fires; and we do hereby declare that the following is a full, clear, and exact description of the invention, that will enable others skilled in the art to which it appertains to make and use the same, reference being had to the accompanying drawings, forming a part of this specification, in which—

Figure 1 shows a side elevation; Fig. 2, a detail; Fig. 3, skeleton plan of frame; Fig. 4, modification of former, &c. Fig. 5 shows a section of the sleeve and pipe.

Same letters show like parts.

Our invention consists of certain improvements on the apparatus for extinguishing fires for which a patent was issued to John B. Logan, November 21, 1876.

Our improvements consist of devices for leveling the platform supporting the apparatus to accommodate it to the inequalities of the ground, devices by which the pipe or tube is elevated after its sections have been coupled together, devices by which said pipe or tube is revolved upon its axis, a device for stiffening and strengthening the same, an improved adjustable nozzle, devices for operating the same, devices for supporting the same in its different positions, and an improved arrangement of valve or cut-off.

Our invention will be best understood by reference to the accompanying drawings, in which—

a shows the wheels of the truck or carriage, supporting upon springs *b* a heavy frame, *c*. Upon this frame, mounted upon journals *d*, one at each end, is a platform or body, *e*. An intermediate journal, *d'*, may also be employed to give increased strength.

At *f* are spindles, secured to the sides of the platform *e*, and passing downward through jaws *g* upon the sides of the frame, which jaws are closed or opened by handles *h*, clutching or releasing the spindles. At *i*, taking the place of a fourth spindle, is a screw passing upward through the frame and operating to elevate or depress the side of the platform, making it oscillate upon its longitudinal axis.

When leveled by means of this screw, it is retained in position by the spindles and jaws before mentioned. Upon this platform is a heavy frame, *j*, carrying mounted upon trunnions *k* a sleeve, *l*, to the bottom of which, at *m*, is attached a T-piece, forming a connecting passage from the hose to the water-pipe. Within this sleeve is the lower section, *n'*, of the stand-pipe *N*, so arranged as to revolve easily, its lower end entering a stuffing-box in the before-mentioned T-piece, or in the lower end of the sleeve. The section, Fig. 6, shows the general arrangement of these parts, though, of course, we do not limit ourselves to any precise form of stuffing-box or means of packing the connection.

The T-piece, to which the hose from the engines or hydrants are attached, always remains stationary and unaffected by the revolution of the pipe *N*, which revolution is communicated to it through a gear, *o*, fastened thereto, by means of a worm, *p*, upon a shaft, *p'*, journaled upon supports or arms secured to the sleeve, enabling the stream to be directed toward any point of the horizon.

Concentric with the trunnion *k*, and bolted to the sleeve *l*, is a segmental gear, *q*, operated by a worm, *q'*, upon a shaft, *q''*, which shaft carries a gear, *q''*, meshing into a pinion upon a shaft, *q'''*, extending to the rear of the machine, at which point it is provided with a hand-wheel, the revolution of which elevates and retains the pipe in a vertical or inclined position, as preferred.

Our device for bracing the pipe consists of a rope, *t*, preferably of wire, attached at its lower end to the pipe *N*, near the point where it enters the sleeve *l*, and extending nearly to the end of the pipe.

Upon the lower section of the pipe *n'* is an arm, *r*, pivoted to said pipe, so as to be out of the way when not in use. A corresponding arm, *r'*, is attached in like manner to the upper section, *n''*. After the pipe has been coupled together the rope *t* is attached at each end of the pipe and the arms *r* *r'* forced out against it, straining it, as shown, and forming a truss, *T*. This, as will be seen, is upon the side toward which the water is delivered by the nozzle, and, being attached at both ends to the pipe, turns with it, always maintaining its po-

sition relative to the stream and bracing the pipe against its reaction.

Our improvement in the adjustable nozzle we consider of great importance. It consists 5 in making a section of the pipe of flexible material, so that as the elevation of the stream is varied the water may be conducted through a curved bend of the pipe, presenting the minimum of resistance to its flow. This section x is preferably placed upon the extremity of the pipe, although it may be attached to an elbow at any intermediate point between base and top. In practice it is about eighteen inches in length, and may be stiffened and strengthened 10 by a spiral spring, like the ordinary suction-hose. It is tipped with the usual nozzle y . The force of the water is sufficient to elevate it to a perpendicular position, or, if desired, springs may be attached for the purpose. If 15 this is done, the manner in which they should be applied will readily suggest itself. This section is drawn down and made adjustable in a vertical plane, so as to control the elevation of the stream, by a cord, z , attached to 20 the nozzle, and having its lower end wound upon a drum provided with appropriate ratchet devices and located near the platform of the machine.

A valve controlling the stream may be 25 placed in the pipe near the point where it enters the sleeve l , the lever 3 operating it being thus within easy reach from the platform, like the drum 1 and the mechanism for giving revolution to the pipe.

30 In order to prevent any break in the flexible portion of the pipe x when the same is depressed, we provide means by which a true curve is maintained when the same is drawn down, thus preventing any impediment to 35 the stream. This may be effected in several ways, one of which is shown in Fig. 1. This consists of a metallic former, 5 , attached to the lower end of the section x , or to the pipe immediately adjacent, which former is concave on its inner surface, in cross-section, to receive the section x . At the upper end of said section is a second former, 6 , reversed in position, serving together to support the section when it is drawn down into a curved position. 40 A modification of this is shown in Fig. 4, in which the upper former, 6 , is shown as bent into an arc of a circle, or nearly so. With this form the former 5 may be dispensed with.

45 A metallic casing or frame, 7 , is attached to the back of the section x , to guard against bulging, and when the modification of the former, Fig. 4, is used, this casing may be extended, as shown in dotted lines at 8 , and provided with slots 9 , serving as guides for the former 50 as it moves downward with the section x .

The valve or cut-off of the stream may be placed at the extremity of the nozzle, as shown in Fig. 4, and it is necessary to provide means for operating the valve from the platform of the apparatus. The method of doing this is 55 shown in Fig. 4.

The cord 2 , before mentioned, is attached to the lever opening the valve, and is then passed down to the lower end of the nozzle y around a pulley, 13 , thence up and around a second 70 pulley or eye, 14 , thence down to the drum, passing, if desired, over a pulley in the former at 15.

Between the pulleys 13 , 14 a stop is attached to the cord 2 , (see 16.) As the cord 75 2 is wound on the drum, as before described, it first passes loosely over the pulleys, acting upon and opening the stop-cock through its lever 12 . When, however, the stop or check 16 comes in contact with the pulley-casing at 80 14 , the further winding of the cord acts upon the flexible section, as before described, drawing it downward. The valve or stop-cock is closed by means of a spring.

We do not limit ourselves to the particular 85 arrangement of pulleys above described, as it may be varied.

It will be observed that although the details of the invention patented to Logan, as before mentioned, have been varied, the fundamental 90 principles have been preserved, both the tube or pipe movable about a vertical axis and delivering the water at an elevation, and the nozzle or nozzles adjustable in a vertical plane, entering into and forming a part of the apparatus herein described.

What we claim as our invention, and desire to secure by Letters Patent, is—

1. The combination of the platform e , supported upon journals d and carrying a fire-extinguishing apparatus, substantially as described, with the spindles f , clamps or jaws g , and adjusting-screw i , as and for the purposes set forth.

2. In an apparatus for extinguishing fires, 100 a pipe, N , supported in a sleeve, l , and capable of rotation therein, in combination with non-rotating connection m , conducting the water to said pipe from the engines or hydrants, substantially as set forth.

3. The combination of the pipe N , supported in a sleeve, l , and capable of rotation therein, with the gear o and worm p , operating as set forth, for the purposes specified.

4. The pipe N , in combination with the brace t and one or more arms, r , forming the truss T , as and for the purposes set forth.

5. In an apparatus for extinguishing fires embodying a pipe, N , receiving water under pressure at its base and movable about a vertical axis, the combination, with said pipe, of a truss, T , attached thereto upon the side toward which the water is delivered and rotating with said pipe, substantially as set forth.

6. The combination of the flexible section x with the curved and concave formers 5 or 6 , operating substantially as set forth, for the purposes described.

7. In an apparatus for extinguishing fires embodying a rigid pipe, having a flexible section, x , the combination, with said section, of supporting devices adapted to preserve a true

curve in said section when the same is drawn down, substantially as and for the described purposes.

8. In combination with the tube *N*, having a flexible or adjustable section, *x*, nozzle *y*, and valve or stop-cock *10*, the cord *2*, with its stop or check *16*, and appropriate guides or pulleys, substantially as and for the described purposes.

In testimony that we claim the foregoing we do have hereunto set our hands this 24th day of May, 1879.

JOHN B. LOGAN.
ABNER GREENLEAF.
